UNITED STATES PATENT OFFICE.

PAUL R. DESCHERE, OF NEW YORK, N. Y., ASSIGNOR TO THE UNION SWITCH & SIGNAL COMPANY, OF SWISSVALE, PENNSYLVANIA, A CORPORATION OF PENNSYLVANIA.

RAILWAY CAB SIGNALING AND TRAIN-CONTROL SYSTEM.

Application filed June 23, 1917. Serial No. 176,457.

This invention relates to railway block signal systems and more particularly to a system of the above type in which the movement of a railway train is automatically controlled in accordance with the condition of the track in advance of said train. With regard to its more specific features, this invention relates to a cab-signaling and train-control system of the type employing 10 alternating currents.

One of the objects of this invention is to provide a practical and effective railway signal system that will combine a high degree of simplicity of construction with 15 maximum reliability of operation.

Another object lies in the provision of a signal system for automatically indicating in a moving railway train the condition of the track in advance thereof, and for automatically controlling the movement of the 20 train according to such conditions.

Another object of this invention is to provide a cab-signaling and train-control system of the above nature, in which effective 25 cooperation between the track signal circuits and the train circuits is accomplished without the use of contact rails or wires, or sliding current collectors on the running rails or rotating equipment.

This invention has for another of its objects the provision of a cab-signaling and train control system of high efficiency of 30 operation and of low energy consumption, without impairment of the reliability of 35 action of said system.

Another object of this invention is to provide means for using effectively apparatus of low energy consumption for a system of the above nature.

Other objects will be in part obvious and 40 in part pointed out hereinafter.

The invention accordingly consists in the features of construction, combinations of elements and arrangement of parts which 45 will be exemplified in the construction hereinafter described, and the scope of the application of which will be indicated in the following claims.

In the accompanying drawings in which 50 is shown one of several possible embodiments of this invention,

Fig. 1 is a diagrammatic representation of a portion of a railway track showing the electric signal circuits associated therewith, 55 and,

Fig. 2 is a diagrammatic representation of the signal and control circuits mounted in a convenient part of the train.

Similar reference characters refer to similar parts throughout.

Referring now to Fig. 1 of the drawings, there is shown diagrammatically a portion of a railway track comprising the rails 3—4, divided into signal sections or blocks 20—40—60—80 of convenient lengths by 60 suitable insulating joints, as at 5—6, for example. Extending parallel to the track 3—4 is a transmission line 7—8 connected to a source of alternating current, preferably of a suitable low frequency convenient 65 for operating track relays of the usual type, one of which as 41, is associated with each signal section as 40. Connected to the transmission line 7—8 and individual to each signal section, as 40, is a track transformer 70 42 comprising a primary winding 43 and two secondary windings 44—45, for transforming the current of the signal circuits from the transmission voltage to a convenient track voltage. The one secondary winding as 44 of the track transformer as 42, is connected to one winding 46 of the relay 41, and serves to energize permanently that 75 winding of the relay. The other secondary winding as 45 of the track transformer is 80 connected through a suitable inductance 47 directly across the rails of the preceding signal section 60, and serves to energize the winding 68 of track relay 61 associated with section 60. Likewise the winding 48 of re- 85 lay 41 associated with the signal section 40 derives its energizing current from the secondary winding 25 of the transformer 22 associated with the section 20, to which secondary it is connected through a suitable 90 inductance 27 and the rails of section 40. Thus, the energization of winding 48 of the 95 relay 41, and hence the operation of the latter, is dependent upon the condition of the track section with which that relay is 100 associated.

Extending likewise parallel to the track 3—4 are the circuits 9—10 and 10—11, which may have one conductor 10 in common, connected respectively to sources of 105 alternating current of differing frequency, which will be designated as "caution" frequency and "clear" frequency respectively. These two frequencies are so selected that, with the frequency of the transmission line 110

7—8, they do not constitute rational multiples of one another, thereby avoiding harmonic interferences therebetween. Furthermore, frequencies of such values are selected that they may be readily separated one from another by suitable resonant circuits to be hereinafter described.

To the circuit 9—10 of caution frequency there is connected primary 50 of a transformer 51, individual to the signal section 40, for transforming from transmission voltage to suitable track voltage. Secondary winding 52 of the transformer 51 is connected through relay 41 to the rails 3—4 of the preceding signal section 60, over the following circuit: from secondary 52, conductor 53, contacts of relay 41, and conductor 54 to rail 3 of section 60; rail 4 of section 60 is connected through conductor 55 back to secondary 52. In this manner a voltage of caution frequency is impressed across the rails of the section 60 preceding the section 40 with which relay 41 is associated.

Likewise the transformer 56 is provided to transform the voltage of the clear frequency circuit 10—11 from line voltage to track voltage. The secondary 57 thereof is connected across the rails 3—4 of the second preceding signal section 80 through contacts of relays 41 and 61, over the following circuit: from secondary 57, conductor 58, contacts of relay 41, conductor 59, contacts of relay 61, conductor 74 to rail 3 of section 80 and from rail 4 over conductor 75 back to secondary 57. In this manner a voltage of clear frequency is impressed across the rails of signal section 80.

In like manner through the entire railway track, all the caution frequency transformer secondaries are connected through the contacts of one track relay to the rails of the preceding signal section, and the secondaries of all clear frequency transformers are connected through the contacts of two track relays to the rails of the second preceding section, each section having impressed across its rails voltages of both caution and clear frequencies.

Suitable condensers and inductances or choke coils are placed in the several circuits to prevent interference between the circuits of different frequency and to prevent reactions of one circuit upon the other.

Turning now to Fig. 2, there are shown the signal and control circuits as mounted in a cab of a railway train, it being understood that by "cab" is meant any suitable or convenient part of the entire train from which the movements of the train may be conveniently controlled. There is shown in Fig. 2 a pair of car wheels 100—101 mounted on the axle 102 and forming a part of the running gear of the train or locomotive, and preferably constituting the lead-

ing pair of wheels and axle of the train. These wheels run on the rails 3—4 and thereby may complete the various circuits through the rails by means of the axle 102, the latter carrying the currents of the circuits completed thereby. Mounted upon the axle 102 and preferably removably suspended from the truck frame with which the axle 102 is associated, is a winding 103 comprising turns of wire wound upon an iron magnetic circuit surrounding the axle 102, and forming thereby a secondary winding of a transformer of which the car axle 102 constitutes the primary.

Connected to the secondary winding 103 of the axle transformer and in multiple with one another, are the primary windings 105 and 106 of the transformers T and T'. In the circuits of the primary windings 105 and 106 are respectively condensers C and C' and inductances L and L' in series therewith. The capacity of the condenser C and the value of the inductance L in the circuit of the primary 105 of transformer T are so adjusted that their associated circuit is in resonance with respect to the caution frequency, and hence the transformer primary 105 will carry a current only of caution frequency, the currents of the remaining frequencies being prevented from passing through the tuned circuit by reason of the values of the capacity and inductance in that circuit. Similarly the circuit of the primary 106 of the transformer T' is resonantly tuned with respect to the current of clear frequency and hence allows transformer primary 106 to respond only to the clear frequency current.

To the secondary windings 105 and 106 of the transformers T and T', respectively, are connected the amplifiers 107 and 108, which may be of the audion type used in wireless telegraph work and which comprise accordingly the batteries B₁—B₂ and B'₁—B'₂, respectively, for intensifying or amplifying the current vibrations received thereby. A second amplifier 110 may be connected with the first amplifier as 108 by means of transformer T₂ for producing a further amplification of the current variations.

Connected to the amplifiers 107 and 110 respectively are the frequency meters 109 and 112, which are preferably of the resistance-reactance or split-phase type and which are of convenient range of operation to respond respectively to the currents of caution frequency and clear frequency. The frequency meter 112 controls, at contacts controlled by the moving element thereof, an auxiliary operating circuit 111 including a battery B'₃ and an electric bell 113, or some other suitable device for visibly or audibly giving an indication. Frequency meter 109 in like manner controls an auxiliary circuit 116 com-

prising a solenoid 114 and the battery B_s , this circuit being opened or closed at suitable contacts operated by the moving element of the frequency meter. Solenoid 114 in turn is adapted to control the operation of the train controlling devices by means of suitable relay apparatus, which devices may constitute the throttle valve in the steam circuit of a steam locomotive or suitable switches in the electric circuit controlling the current to the propulsion motors in the case of an electric train. Preferably the device controlled by the solenoid 114 is the air valve controlling the air brakes throughout the entire train.

The operation of this system is substantially as follows: Normally each signal section as 80 has impressed upon it the voltages of caution frequency and clear frequency over circuits similar to those previously described and controlled by the several track relays. A train approaching in section 80 in the direction indicated by the arrow 115 will close the circuits of caution frequency and clear frequency, of which circuits the rails 3-4 of section 80 form a part, through an axle 102 of the train. The alternating currents of both caution and clear frequencies pass through the axle 102, which forms the primary winding of the car axle transformer. Currents of the same frequencies are induced in the secondary winding 103 and are conducted to the cab signal circuits. The current of caution frequency will pass through the primary 105 of the transformer T through the circuit comprising the condenser C and the inductance L, the magnitudes of which, as heretofore described, are adjusted to give a resonant condition with a current of caution frequency. Currents of clear frequency, as well as of the frequency of the transmission line which may be induced in the secondary 103 of the car axle transformer, are prevented from passing through the primary 105 by reason of the circuit in series therewith. Hence, a current of caution frequency will be induced in the secondary 117 of the transformer T, to which the amplifier 107 is connected. The amplifier 107 will intensify or amplify the variations or oscillations of current of caution frequency and will transmit such amplified current to the frequency meter 109, thus causing the meter to indicate constantly the caution frequency and to hold closed the circuit 116. Similarly, by reason of the characteristics of the circuit of the primary 106 of the transformer T', the primary 106 will receive only current of clear frequency, the currents of other frequencies being substantially tuned out. Currents of clear frequency will be induced in the secondary 119 of transformer T', the variations thereof being amplified successively by the amplifiers 108 and 110, and then transmitted to the frequency meter 112. Meter 112 will accordingly give a constant indication of the clear frequency and will hold open at its associated contacts the auxiliary operating circuit 111. Hence with both caution and clear frequencies affecting the frequency meters 109 and 112, the auxiliary operating circuits are held closed and open respectively, and the circuits controlling the train control apparatus held inoperative, allowing free advance movement of the train.

If, however, a train be present in the section 40, the on-coming train in section 80 will receive an immediate indication of the presence of a train in the second section in advance thereof. A train in section 40 short-circuits the winding 48 of relay 41 associated with the section 40. Relay 41 being then under the influence of coil 46 only, thereupon operates to open its associated contacts, thereby opening the circuit of the clear frequency current, previously traced, impressed upon the rails of section 80. The clear frequency current is thereby cut off from the signal circuit in the train cab, leaving only the current of caution frequency in its respective circuit. The moving element of frequency meter 112, responsive to clear frequency immediately moves to zero indication upon the cessation of the current of clear frequency and closes the auxiliary operating circuit 111 at its associated contacts to operate an electric bell 113 to indicate audibly the presence of a train in the second section ahead, thus indicating to the operator the necessity for proceeding with caution.

If, on the other hand, there is a train in the section 60 immediately ahead of the section 80 of the approaching train, track relay 61 is operated by reason of the short-circuiting by the train in section 60 of the winding 68, thereby opening at its associated contacts the circuits of both caution and clear frequency impressed upon section 80. These circuits are similar to those previously described. Track relay 61 then removes from section 80 the currents of both caution and clear frequencies, whereupon both frequency meters 109 and 112 return their moving elements to zero. Frequency meter 112 closes the circuit 111 to the electric bell 113 to give an audible indication of danger and frequency meter 109 opens at its associated contacts the circuit 116 to the solenoid 114 to operate preferably the air valve 118 in the air brake circuit of the train, thereby bringing the train to a stop. The solenoid 114 is so connected with the air valve 118 that a de-energization thereof, either by the opening of its circuit by the meter 109 or by an accidental rupture of its circuit, will actuate the valve 118 to cause the operation of the brakes of the train.

It is to be noted that current from the transmission line 7-8 is always induced in coil 103 on the railway car axle. Under certain conditions, a harmonic of the frequency of this current may approximate that to which circuit 105 or 106 is tuned and an appreciable current may be induced in secondary 117 or 119. If in such case the ordinary electro-magnetic relay were employed, in secondary circuits 117 and 119, one of these relays might operate to indicate danger or to throttle the engine also, while the road ahead is unobstructed.

In the embodiment of this invention herein set forth, only one track of a multiple track system is shown with its associated signal circuits, but it is to be understood that similar signal circuits may be readily applied to the other tracks of such a multiple track railway. It is to be noted that a single signal circuit may be employed instead of the two circuits herein shown without departing from the spirit of this invention.

It will be seen that there is provided herein a train signaling and control system in which the condition of the track in advance of an approaching train is positively indicated at all times in the train itself and in which the further movement of the train is controlled automatically according to such track conditions. Furthermore, it will be noted that the control circuits and signal circuits associated therewith, are preferably of the closed circuit type, whereby a maximum reliability of operation and safety is attained, since either an intentional or accidental breakage of a circuit will immediately give a danger signal and bring the train to a stop. It is also to be noted that a signal and control system has been provided, which may be used with direct current as well as with alternating current installations, and that this system is easily adapted to employ the many forms of signaling apparatus and devices used in railway signal work. It will further be seen that there is provided a system in which the several and other advantageous objects of this invention are effectively achieved.

As various possible embodiments might be made of the above invention and as various changes might be made in the embodiment above set forth, it is to be understood that all matter herein set forth or shown in the accompanying drawings is to be interpreted as illustrative and not in a limiting sense.

I claim as my invention:

1. In a railway locomotive, a signal circuit, means for communicating currents of different frequencies, from a main track circuit to said signal circuit, means in said signal circuit responsive to one frequency for indicating a track condition, and means in said circuit responsive to another frequency

for controlling the motive means of said locomotive.

2. In a railway block signal system, a track divided electrically into signal sections, a plurality of current sources of different frequencies, and means associated with and controlled by each of said sections for connecting one of said sources to a preceding section and another of said sources to a section preceding said last section. 75

3. In a railway block signal system, a track divided electrically into signal sections, a track circuit associated with said signal sections, a relay operatively related with said track circuit and with each of 80 said signal sections and adapted to be controlled by its associated signal section, a plurality of current sources of varied frequencies, one of said sources being connected through said relay to the preceding signal 85 section, and another of said sources being connected through said relay to the signal section preceding said last section.

4. In a railway signal system, a track divided electrically into signal sections, a 90 track circuit associated with said signal sections, a relay operatively related with said track circuit, with each of said signal sections and adapted to be controlled thereby, a plurality of current sources of varied frequencies, said relays controlling the connection of said sources to said signal sections; signal circuits in a railway car each of which is adapted to respond to one of said frequencies, means for communicating said currents from said signal sections to said signal circuits, a device for indicating the frequency of said currents in each of said signal circuits, and auxiliary operating circuits controlled by said devices. 100

5. In a railway signal system, a track divided electrically into signal sections, a track circuit associated with said signal sections, a relay operatively related with said track circuit, with each of said signal sections and adapted to be controlled thereby, a plurality of current sources of varied frequencies, said relays controlling the connection of said sources to said signal sections; signal circuits in a railway car each of which is adapted to respond to one of said frequencies, means for communicating said currents from said signal sections to said signal circuits, a device for indicating the frequency of said currents in each of said signal circuits, and an auxiliary operating circuit connected to each device, each said circuit being adapted to function when the corresponding device indicates an associated frequency. 110

6. In a railway signal system, in combination, a plurality of circuits normally carrying currents of different frequencies, indicating devices in a railway car, one responsive to each of said currents, means ac- 120 130

tuated by the presence of a train preceding said car for breaking one of said circuits, and other means similarly actuated for breaking other said circuits.

5 7. In a railway signal system, in combination, a pair of circuits for carrying alternating currents of different frequencies, electromagnetic switches in said circuits for normally maintaining them closed, and another circuit under the influence of a train for actuating said switches to open said pair of circuits.

8. In a railway signal system, in combination, a pair of circuits for carrying alternating currents of different frequencies, indicating devices in a railway car, one responsive to each of said currents, an electromagnetic switch in each of said circuits, and means for permitting the axle of a pre-

ceding train to short-circuit a coil of said switch to affect said circuits.

9. In a railway block signal system, in combination, a section of traffic rails constituting a block, a source of current energizing said section, a coil across said rails, two pairs of switch contacts under the influence of said coil, an alternating current circuit of a definite frequency passing through one pair of contacts to the preceding block, and a second alternating current passing through said other pair of contacts to the block preceding said latter block.

In testimony whereof, I have signed my name to this specification this 20th day of June, 1917.

PAUL R. DESCHERE.
